UNITED STATES PATENT OFFICE.

ARTHUR F. PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY.

METHOD AND MEANS FOR POSITIONING LASTS AND THEIR SHOE MATERIALS.

Application filed February 12, 1925. Serial No. 8,717.

This invention relates to the positioning of lasts and their shoe materials relatively to means for operating on the materials. The invention is herein illustrated in its application to the operation of lasting the toes of shoes, for which it has very important advantages, but it will be understood that the invention is not limited to that particular part of shoe manufacture.

10 In lasting the toes of shoes in machines of well-known types provided with toe-embracing wipers that are shaped to conform substantially to the contour of the toe when they are closed about the toe, it is important for satisfactory results that the shoe and the wipers be positioned relatively to each other with a high degree of accuracy, both in respect to the relation, as to angularity, between the bottom face of the shoe and the 15 plane of the wipers in the wiping of the upper inwardly over the insole and in respect to the relation between the end and the sides of the toe and the edges of the wipers. Machines have accordingly been provided 20 with means for adjusting the shoe positioning means and the wipers in various ways, and it is necessary for the operator to make use of some or all of these adjustments in changing from one size or style of shoe to another, and also frequently to make one or more adjustments to compensate for variations in position as between different shoes 25 of the same size and style. This takes much of the operator's time, with consequent limitation in the amount of production. Since, 30 moreover, there is nothing to afford the operator any very definite indication of the best relation between the shoe and the wipers, the quality of the results obtained in the lasting operation depends very largely upon the operator's care and judgment. Lack of 35 uniformity in the product and frequent deviations from the best workmanship are therefore almost inevitable even with the most highly skilled operators.

In one important aspect the present invention provides a method by the use of which lasts and their shoe materials are positioned quickly and accurately in the best relation to the means for operating on the materials without the need for any high degree of care or skill on the part of the operator, thus improving the quality of the work, increasing the output, and at the same

time permitting machines to be much simplified by eliminating provision for various adjustments. In accordance with this method, as herein exemplified, the last and the machine are each provided with a plurality of positioning surfaces in spaced locations, 55 those on the last bearing a predetermined relation to the contour of the last and those on the machine bearing a correspondingly predetermined relation to the means for operating on the shoe materials, and the last 60 and its shoe materials are positioned by engaging the positioning surfaces on the last with the corresponding positioning surfaces on the machine. For the purposes in view, the last may be provided, as herein shown, 65 with a plurality of holes in the bottom of its forepart and the machine may have a plurality of pins to enter these holes and thus position the last. It will be understood that the 70 holes will be arranged in a definitely predetermined relation to one another and to the edge contour of the last bottom, and the pins will be arranged in a correspondingly predetermined relation to one another and also, 75 as herein illustrated, in a predetermined relation to the toe wipers such that when the wipers have been advanced and closed a 80 definite distance their wiping edges will conform substantially to the contour of the toe of the shoe at the edge of the shoe bottom. The position of the last in respect to lengthwise and lateral bodily movements and in 85 respect to lateral swinging movements is thus definitely determined.

Further to insure a definitely predetermined relation, as to angularity, between the bottom face of the forepart of the last and the plane of the wipers in the wiping of the upper inwardly over the bottom of the last, the pins and the holes in the last, as the invention is herein exemplified, are utilized to determine the position of the last in respect to tipping movements about axes extending lengthwise or laterally thereof, the end faces of the pins engaging the last at the bottoms 100 of the holes and the latter extending into the last to predetermined relative depths calculated in accordance with the relation, as to angularity, which it is desired that the bottom of the last or shoe shall assume to 105 the plane of the wipers. For the purpose of this part of the invention, it is contemplated that at least three pins will be uti-

lized, with a corresponding number of holes in the last. It will be recognized that the pins will determine also the position of the last as a whole in respect to movement in the direction of its height, and preferably the last will be held securely in the position determined by the pins.

Where, as in toe lasting, the shoe materials under treatment include an insole, the insole will be provided with holes in its forepart which correspond to the holes in the last and receive the last positioning pins, the holes in the insole, formed in predetermined relation to its edge contour, also affording in co-operation with the holes in the last an accurate indication of the proper position of the insole on the last in assembling the parts. After the insole has been positioned so that its holes aline with the holes in the last, it may be tacked to the last in the usual way.

In addition to its method aspects the invention, in still other aspects, resides in improved apparatus useful in carrying out the method and characterized, for example, by the provision, in a machine for operating on shoe materials on a last, of a plurality of last-positioning pins, such as those above referred to, for positioning the last relatively to the operating means, the machine herein shown having also means for clamping the last against the ends of the pins. The invention further provides features of novelty both in lasts and in insoles adapted for use in the practice of the method.

The invention will now be more particularly described by reference to the accompanying drawings and pointed out in the claims.

40 In the drawings:—

Fig. 1 is a plan view of toe-embracing wipers and shoe positioning means, illustrating how the last and its shoe materials are positioned in a toe lasting machine by the method of this invention through the use of one form of positioning means that may be utilized in practicing the method;

Fig. 2 is a cross-section through the last and shoe and through the shoe positioning means and the wipers at one stage in the operation of the wipers on the shoe;

Fig. 3 is a view of the parts shown in Fig. 2, partly in side elevation and partly in section longitudinally of the shoe;

Fig. 4 is a view on a smaller scale than Figs. 2 and 3 of a last utilized in practicing the method, illustrating also how the positions of the holes in the last may be determined; and

Fig. 5 shows an insole utilized in the practice of the method.

The toe lasting mechanism shown for illustrative purposes in Fig. 1 comprises toe-embracing wipers 2 mounted on wiper holders 4 which are movable in curved guide-

ways formed in a wiper carrier 6 mounted for movements lengthwise of the shoe. The wiper carrier 6 is provided with pinions 8 engaging rack teeth formed on the wiper holders 4 and operated by a rack bar 10 to close the wipers about the toe. This mechanism is of the same construction as shown in my co-pending application Serial No. 698,099, filed on March 10, 1924, which further shows and describes in detail operating mechanism for imparting advancing and closing movements to the wipers. It is sufficient for an understanding of the present invention to state that, as usual in machines of the same general type, the wipers receive advancing movement lengthwise of the shoe and closing movements laterally of the shoe such that for a given amount of advancing movement there is a predetermined amount of closing movement. As usual also in toe lasting machines, the wipers are shaped at their wiping edges substantially to conform to or to fit the contour of the toe of the shoe when they have been advanced and closed about the toe substantially to the edge of the shoe bottom ready to begin the wiping of the upper inwardly over the insole. For the best results, differently shaped wipers will preferably be substituted for different shapes and sizes of shoes, although under some conditions it is practical to use the same wipers for several different sizes. To accommodate the wipers to different widths of toes, means may be provided for adjusting the wipers about the axis of their closing movement, such means being described in the co-pending application above referred to. As shown also in said application, the wipers will preferably be mounted for movements heightwise of the toe to upwipe the upper to the edge of the shoe bottom and later to press the upper down upon the margin of the insole, as well as for advancing and closing movements to wipe the upper inwardly over the insole.

It will be evident that if the wipers are to conform with substantial accuracy to the contour of the toe when they have been advanced and closed a definite distance, the shoe must be in a definite predetermined relation to the wipers at that point in their operation, and it will also be evident that satisfactory results in the wiping of the margin of the upper inwardly over the insole require a certain predetermined relation, as to angularity, between the bottom face of the forepart of the shoe and the plane of the wipers. Generally speaking, it is desirable that the wipers shall bear evenly upon the margin of the upper about the end and along the sides of the toe with substantially or approximately equal pressures in these different locations, although it may be desired under some conditions for the wipers to bear on the upper with some-

what greater pressure in one location than in others, for example at the end of the toe as compared with the sides of the toe. By the present invention the position of the last and its shoe materials in these different respects is accurately predetermined, so that as far as the position of the work is concerned the best results are insured.

For the purposes in view, the last 12 is provided with a plurality of holes 14 in its bottom portion, as herein shown in the bottom of its forepart, to be utilized in positioning the last in respect to lengthwise and lateral bodily movements and lateral swinging movements, and also in respect to lengthwise and lateral tipping movements. The holes 14 are shown as formed in metal bushings 16 which are inserted in holes 17 formed in the wood of the last to receive them.

While the invention is not limited to the use of three holes in the last, as herein shown, it is considered that this number of holes is adapted to give the best results in positioning the last in the different respects desired.

It will be observed that one of the holes 14 is located near the end of the toe, substantially midway between the opposite sides of the toe, and that the other two holes are located farther rearwardly, for example about where the tip seam will come on the shoe, and are near the opposite sides of the toe.

It will be evident, from further consideration hereinafter of the manner in which the holes 14 in the last are utilized in positioning the work, that the distances between the holes and their relations to one another and to the contour of the last may be varied, within limits, as long as the elements co-operating with the holes in positioning the work are correspondingly positioned in relation to one another and to the means for operating upon the shoe materials, although it is preferable that the holes be located as near to the edge of the last bottom as it is practicable to position them. The distances of the holes from the edge of the last bottom will, however, be so determined, on welt work, that corresponding holes 18 punched in the forepart of the insole 20 will be positioned inside of the rib or lip 22 of the insole. It will be understood that the holes 18 in the insole will be located in the same relation to the edge of the insole that the holes 14 in the last bear to the edge of the last bottom. It is preferable that the holes 18 in the insole be located near the lip or rib, but since it is contemplated that, for convenience, several different sizes of lasts may have holes the same distances apart, the holes in the insole may be located nearer to the rib in some sizes than in others. A machine that may be utilized for punching the holes in the insole is shown in a copending application, Serial No. 15,093, filed on March 12, 1925.

It is important that the holes 14 be located in the same relation to the edge contour of the last bottom in all lasts of the same size and style, and to this end it is contemplated that the different lasts will be positioned in the same relation to a group of tools provided for boring the holes 17 in the wood of the lasts, by the use of suitable gaging mechanism comprising, for example, members 24 shown diagrammatically in Fig. 4 for engaging the last at the end and the sides of the toe. In view of the manner in which the holes 14 are utilized in determining the relation of the bottom face of the forepart of the last to the plane of the wipers, it is important to gage accurately the depths of the different holes. Conveniently the metal bushings 16 provided for insertion into the holes 17 in the wood of the last may be all alike, with the inner ends of their holes 14 spaced equal distances from their bottom or inner end faces, and the distances to which the holes 14 extend into the last will accordingly depend upon the depths of the holes 17 in the wood of the last. In the toe lasting operation it is important to determine the relation between the plane of the wipers and only a comparatively narrow margin of the shoe bottom about the end and along the sides of the toe, and it is, therefore, with reference to this particular portion of the bottom face of the last that the depths, and likewise the directions, of the holes 17 in the wood of the last are determined. Practically this may be accomplished by the use of gages contacting with the bottom face of the forepart of the last near the edge of the last bottom at the end and the sides of the toe, and in Fig. 4 the gage members 24 which engage the last at the end of the toe and in the approximate location of the tip seam of the shoe are illustrated as shaped for thus engaging the bottom of the last and additionally determining the position of the last, relatively to the tools for boring the holes 17, in respect to lengthwise and lateral tipping movements. These gages thus determine a plane on the last represented by the dotted lines A and B on Figs. 2 and 3 respectively, which may be termed the plane of the forepart of the last bottom, and the depths and directions of the holes 17, and consequently of the holes 14, will bear a predetermined relation to this plane. In view of the fact that lasts are usually more or less convex on their bottom faces at the forepart, as illustrated, it will be evident that the different holes will usually not extend into the last for equal distances relatively to adjacent portions of the bottom face of the last. The metal bushings provided will be of such length as to allow for such variations in depth, and after they have been seated at the bottoms of the holes 17, they will be ground off so

as to be flush at their outer ends with the bottom surface of the last. A machine that may be utilized for boring the holes in the lasts and for gaging accurately the locations and depths of the holes in the manner illustrated diagrammatically in Fig. 4, and also for inserting the bushings, forms the subject-matter of a copending application Serial No. 14,756, filed on March 11, 1925.

10 To co-operate with the holes 14 in positioning the last and its shoe materials, pins 26 are utilized to project through the holes 18 in the insole and into the holes 14 in the last. These pins, in the construction herein shown, are fast on a plate 28 which is detachably secured by means of a bolt 30 and a locating pin 32 to an arm 34 fast on the frame of the machine. The shoe is supported and the last is clamped up against the ends of the pins 26 by means of a toe rest 36 which may be operated in the manner disclosed in the co-pending application Serial No. 698,099 hereinbefore mentioned.

15 The pins 26 are so located in relation to the wipers that when the wipers have been advanced and closed the correct distance for their wiping edges to conform to the shape of the toe of the shoe at the edge of the shoe bottom, the pins bear the same relation to the wiping edges that the holes in the last bear to the lateral periphery of the toe of the shoe, and thus the shoe is positioned in exactly the right relation to the wipers in respect to lengthwise and lateral bodily movements and lateral swinging movements. It will be further understood that the ends of the pins 26, seating against the metal bushings 16, determine the relation, as to angularity, between the bottom face of the forepart of the shoe and the plane of the wipers in the overwiping operation. The end faces of the pins may lie, for example, as herein shown, in a plane which is parallel to the plane of the wipers when the wipers are in position to wipe the upper inwardly over the insole, and if the plane determined by the inner ends of the holes 14 is parallel to the plane of the forepart of the last bottom represented by the lines A and B, as also herein shown, the latter plane will be parallel to the plane of the wipers in the lasting operation and the wipers will bear evenly on the upper with substantially equal pressures at the end and the sides of the toe. It will be understood that any one of the pins 26 could be longer than shown in the drawings, provided the hole 14 co-operating with the pin were correspondingly deeper, without affecting the position of the last, although it is preferable, for convenience, that the end faces of the pins lie in a plane that is parallel to the plane of the wipers in the overwiping operation. It will be further understood that, having regard to the distance that the pins

17 extend below the plane of the wipers, the holes in the last will be of such depths as to position the last at the proper height relatively to the wipers.

18 By suitably gaging the position of the last relatively to the tools for boring the holes in the last, the holes may be so formed that the plane of the forepart of the last bottom, represented by the lines A, B, will not be in parallel relation to the plane determined by the inner ends of the holes and, therefore, will not be in parallel relation to the plane of the wipers in the overwiping operation. In this way there may be determined such a relation between the shoe and the wipers as to cause the wipers to bear on the upper materials with harder pressure at the end of the toe, for example, than at the sides of the toe, as is desirable on some kinds of work. It will be understood that after it has been determined what pressure applying relation between the wipers and the different portions of the toe is most desirable, all the lasts of the same size and style for a line of shoes will be positioned in the same relation to the boring tools so that the different shoes will be positioned in standardized relation to the wipers.

19 For wide variations in sizes it will be preferable to vary the spacing of the holes 14, and different sets of pins 26 mounted on plates 28 will be correspondingly provided for attachment to the arm 34. Preferably the hole 14 at the end of the toe will be positioned at the same distance from the end face of the last in all sizes of lasts, so that the wipers will be advanced the same distance to bring them up to the end of the toe irrespective of the size of the shoe. It will then only be necessary to adjust the wipers toward or from each other for different widths, as may readily be done, for example, by the mechanism shown in the copending application Serial No. 698,099.

20 In assembling the insole on the last its holes 18 will be brought into alignment with the holes 14 in the last and tacks may then be driven in the usual way to fasten the insole. In performing the toe lasting operation all that the operator has to do in positioning the shoe is to bring it into position for the pins 26 to enter the holes 14, and with the shoe clamped up against the pins by the toe rest 36 assurance is afforded that the shoe is in exactly the right position for the operation of the wipers without the necessity for the operator to give any attention to relative adjustment of the shoe and the wipers, assuming that the wipers have already been adjusted in proper relation to the sides of the toe for the size of shoe upon which the machine is to operate. A further very important advantage is that the pins 26 hold the shoe unyieldingly throughout the lasting operation against

pressures directed lengthwise and laterally thereof.

While the invention is herein illustrated in its application to toe lasting operations, it will be understood that the invention is not thus limited but is likewise applicable to the positioning of shoes for pulling-over and lasting operations and for other operations where it is desirable to position the shoe in accurately predetermined relation to the means for operating upon it. It is likewise to be understood that the invention is not limited to welt shoe work, but is applicable to the manufacture of various types of shoes.

Having described the invention, what I claim as new and desire to secure by Letters Patent of the United States is:—

1. That improvement in methods of positioning a last and its shoe materials relatively to means for operating on said materials, which consists in providing the last with a plurality of holes in its bottom portion, and by engaging the last in said holes positioning it relatively to the operating means in respect to lengthwise and lateral bodily movements and lateral swinging movements.

2. That improvement in methods of positioning a last and its shoe materials relatively to means for operating on an end portion of said materials, which consists in providing the corresponding end of the last with a plurality of holes in its bottom portion in predetermined relation to its contour, and positioning the last relatively to the operating means by engaging it in said holes.

3. That improvement in methods of positioning a last and its shoe materials relatively to means for operating on the toe end portion of said materials, which consists in providing in the bottom of the forepart of the last three holes located respectively near the end of the toe and near the opposite sides of the last, and by engaging the last in said holes positioning it relatively to the operating means.

4. That improvement in methods of positioning a last and its shoe materials relatively to toe-embracing wipers shaped to conform substantially to the contour of the toe of the shoe when they are closed about the toe, which consists in providing in the bottom of the last a plurality of holes in predetermined relation to the lateral contour of the toe, and positioning the last by engaging it in said holes with pins so located as to bear the same relation to the edges of the wipers when the wipers are closed about the toe that the holes in the last bear to the lateral contour of the toe.

5. That improvement in methods of positioning a last and its shoe materials relatively to means for operating on said materials, which consists in providing in the bottom of the last a plurality of holes in

predetermined relation to the lateral contour of the last, providing an insole with holes in such relation to its edge contour as to aline with the holes in the last when the insole is in proper position on the last, and by the use of pins positioned independently of the last and projecting through the holes in the insole into the holes in the last positioning the last and its shoe materials relatively to the operating means. 75

6. That improvement in methods of positioning a last and its shoe materials relatively to means for operating on the toe portion of said materials, which consists in providing in the bottom of the forepart of the last a plurality of holes located respectively near the end of the toe and near the opposite sides of the last and so positioned as to aline with points on a welt shoe insole located inside of the rib of the insole, 80 providing the insole at said points with corresponding holes to aline with the holes in the last when the insole is in proper position on the last, and by the use of pins projecting through the holes in the insole 85 into the holes in the last positioning the last and its shoe materials relatively to the operating means through engagement of the pins with the walls of said holes.

7. That improvement in methods of positioning a last and its shoe materials in a machine having means for operating on said materials, which consists in determining on the machine and on the last respectively groups of points so located that the points 95 of one group coincide with corresponding points of the other group when the last and its shoe materials are in proper relation to the operating means, providing at one group of such points a plurality of pins and at the 100 other group a plurality of holes to receive the pins, and positioning the last by bringing said pins and holes into registry with one another.

8. That improvement in methods of positioning a last and its shoe materials relatively to toe-embracing wipers shaped to conform substantially to the contour of the toe of the shoe when they are closed about the toe, which consists in providing a plurality of pins in predetermined relation to the wipers and extending in directions transverse to the plane of the wipers, providing the last with a plurality of holes in its bottom portion so located as to aline with said 110 pins when the shoe and the wipers are in proper relation for the wipers to conform to the contour of the toe, and positioning the last relatively to the wipers by bringing it into position for the pins to enter said holes. 115

9. That improvement in methods of positioning an insole upon its last, which consists in providing a plurality of holes in the bottom of the forepart of the last in predetermined relation to the lateral contour of the 120 125 130

toe of the last, providing the insole with holes in predetermined relation to its edge contour to aline with the holes in the last when the insole is in proper position on the last, and positioning the insole by bringing its holes into alinement with the holes in the last.

10. That improvement in methods of positioning a last and its shoe materials relatively to means for operating on said materials, which consists in providing in the bottom of the last a plurality of holes of predetermined relative depths, and by engaging the last at the inner ends of said holes determining its position in respect to tipping movements about axes extending lengthwise or laterally thereof.

11. That improvement in methods of positioning a last and its shoe materials relatively to means for operating on said materials, which consists in providing in the bottom of the last at least three holes at points that are out of alinement with one another, and by engaging the last at the inner ends of said holes determining its position in respect to tipping movements about axes extending lengthwise or laterally thereof.

12. That improvement in methods of positioning a last and its shoe materials relatively to means for operating on said materials, which consists in providing a plurality of pins in predetermined relation to the operating means, providing in the bottom of the last a plurality of holes corresponding to said pins, and positioning the last by clamping it against the ends of the pins in said holes.

13. That improvement in methods of positioning a last and its shoe materials relatively to means for operating on said materials, which consists in providing in predetermined relation to the operating means at least three pins located at points that are out of alinement with one another and with their ends in a predetermined plane, providing in the bottom of the last a plurality of holes corresponding to said pins and of predetermined relative depths, and determining the position of the last in respect to tipping movements about axes extending lengthwise or laterally thereof by engaging it with the ends of the pins in said holes.

14. That improvement in methods of positioning a last and its shoe materials relatively to toe-embracing wipers, which consists in providing in the bottom of the forepart of the last a plurality of holes of predetermined relative depths, and determining the relation, as to angularity, between the bottom of the forepart of the last and the plane of the wipers in the overwiping operation by engaging the last at the inner ends of said holes.

15. That improvement in methods of positioning a last and its shoe materials rela-

tively to toe-embracing wipers, which consists in providing in the bottom of the forepart of the last a plurality of holes the depths of which are in predetermined relation to a plane defined by three points on the bottom of the last at the end and at the opposite sides of the toe respectively, and by engaging the last at the inner ends of said holes determining the relation, as to angularity, between the bottom face of the toe of the last and the plane of the wipers in the overwiping operation.

16. That improvement in methods of positioning a last and its shoe materials relatively to toe-embracing wipers, which consists in providing at points that are out of alinement with one another at least three pins with their end faces in a plane bearing a predetermined relation to the plane of the wipers when the wipers are in position for the overwiping operation, providing in the bottom of the forepart of the last a plurality of holes corresponding to said pins and of depths determined with reference to the relation, as to angularity, desired between the bottom face of the toe of the last and the plane of the wipers, and positioning the last by engaging it with the ends of the pins in said holes.

17. That improvement in methods of positioning a last and its shoe materials relatively to toe-embracing wipers, which consists in providing in the bottom of the forepart of the last at least three holes located at points which are out of alinement with one another and with the inner ends of the holes in a plane substantially parallel to a plane determined by three points on the bottom of the last located respectively at the end and at the opposite sides of the forepart, providing a corresponding number of pins in predetermined relation to the wipers with their ends in a plane substantially parallel to the plane of the wipers in the overwiping operation, and positioning the last by engaging it with the ends of the pins in said holes.

18. That improvement in methods of positioning a last and its shoe materials relatively to toe-embracing wipers shaped to conform substantially to the contour of the toe when they are closed about the toe, which consists in providing in the bottom of the forepart of the last a plurality of holes in predetermined relation to the lateral contour of the toe and of predetermined relative depths, providing a plurality of pins so mounted as to bear the same relation to the edges of the wipers when the wipers are closed about the toe that the holes in the last bear to the lateral contour of the toe and with the ends of the pins in a plane bearing a predetermined relation to the plane of the wipers in the overwiping operation, and positioning the last by clamping it against the ends of the pins in said holes.

19. That improvement in methods of positioning a last and its shoe materials relatively to means for operating on said materials, which consists in providing in the bottom of the last at points that are out of alinement with one another at least three holes of predetermined relative depths, and by the use of pins engaging the last in said holes by their end and side faces determining the position of the last in respect to angular movements in all directions. 50
20. That improvement in methods of positioning a last and its shoe materials in a machine for operating on said materials, which consists in providing the last and the machine each with a plurality of positioning surfaces in spaced locations and in predetermined relations respectively to the contour of the last and to the means for operating on the shoe materials, and positioning the last and its shoe materials by engaging the positioning surfaces on the last with the corresponding positioning surfaces on the machine. 15
21. That improvement in methods of positioning a last and its shoe materials in a machine for operating on said materials, which consists in providing the last and the machine each with a plurality of positioning surfaces in spaced locations and so arranged as to determine the position of the last in respect to angular movements in different directions including tipping movements about axes extending lengthwise or laterally thereof, and positioning the last and its shoe materials by engaging the positioning surfaces on the last with the corresponding positioning surfaces on the machine. 30
22. That improvement in methods of positioning lasts of different sizes and their shoe materials relatively to toe-embracing wipers, which consists in providing in the bottom of the forepart of each last a plurality of holes located respectively near the end of the toe and near the opposite sides of the last, with the end holes at equal distances from the toe ends of the lasts irrespective of the size and with the side holes the same distances apart and at correspondingly varying distances from the sides of the lasts in the different sizes, and positioning the different lasts relatively to the wipers by the use of a single group of pins mounted in predetermined relation to the wipers and engaging the lasts in said holes. 45
23. In a machine for operating on shoe materials on a last, the combination with means for operating on the materials, of means for positioning the last and its shoe materials relatively to said operating means by engaging the last within a plurality of recesses formed in its bottom portion. 60
24. In a machine for operating on shoe materials on a last, the combination with means for operating on the materials, of means for positioning different lasts and their shoe materials relatively to said operating means comprising a plurality of pins mounted in predetermined relation to said operating means and arranged to enter corresponding recesses in the bottoms of the different lasts. 70
25. In a machine for operating on shoe materials on a last, the combination with means for operating on the materials, of means for positioning different lasts and their shoe materials relatively to said operating means comprising a plurality of pins arranged to enter recesses in the bottoms of the different lasts, and means for supporting the lasts each in the position determined by said pins. 15
26. In a machine for operating on shoe materials on a last, the combination with means for operating on the materials, of means for positioning a last and its shoe materials relatively to said operating means comprising at least three pins located at points that are out of alinement with one another and arranged to enter recesses of predetermined relative depths in the bottom of the last, and means for clamping the last against the ends of said pins to determine the plane in which a portion of the bottom face of the last is presented. 30
27. In a toe lasting machine, the combination with toe-embracing wipers, of a plurality of pins mounted in predetermined relation to the wipers and arranged to enter holes in the bottoms of the foreparts of different lasts to position the lasts and their shoe materials relatively to the wipers, and a toe rest for supporting each last in the position determined by the pins. 45
28. In a toe lasting machine, the combination with toe-embracing wipers, of three pins mounted in predetermined relation to the wipers and arranged to enter holes in the bottom of the forepart of a last near the end and near the opposite sides of the toe respectively to position the last relatively to the wipers. 100
29. In a toe lasting machine, the combination with toe-embracing wipers, of a plurality of pins mounted in predetermined relation to the wipers and arranged to extend in substantially perpendicular relation to the plane of the wipers when the wipers are in position to wipe the upper inwardly over the insole, said pins being formed to engage a last in holes formed in the bottom of its forepart to position the last and its shoe materials relatively to the wipers. 115
30. In a toe lasting machine, the combination with toe-embracing wipers, of means for positioning a last and its shoe materials relatively to the wipers comprising a group of at least three pins extending in directions substantially perpendicular to the plane of the wipers when the wipers are in position 125
- 130

to wipe the upper inwardly over the insole and arranged to enter holes formed in the bottom of the forepart of the last near the end and near the opposite sides of the toe 5 respectively, the ends of said pins lying in a plane substantially parallel to the plane of the wipers in the overwiping operation.

31. In a toe lasting machine, the combination with toe-embracing wipers, of a group 10 of pins mounted in predetermined relation to the wipers and arranged to enter holes in the bottom of the forepart of a last to position the last and its shoe materials relatively to the wipers, said group of pins being detachable from the machine to permit 15 a group of differently arranged pins to be substituted.

32. The combination of toe-embracing wipers having wiping edges formed substantially to fit the contour of the toe of a shoe when they are closed about the toe, a plurality of last-positioning pins mounted in predetermined relation to the wipers, and a last having in the bottom of its forepart 25 a plurality of holes formed to receive said pins and so located as to bear the same relation to the contour of the toe that the pins bear to the edges of the wipers when the wipers are closed about the toe.

33. The combination of toe-embracing wipers having wiping edges formed substantially to fit the contour of the toe of a shoe when they are closed about the toe, a group of last-positioning pins arranged with 30 their end faces in a plane in predetermined relation to the plane of the wipers when the wipers are in position to wipe the upper inwardly over the insole, a last having in the bottom of its forepart a plurality of 40 holes of predetermined relative depths to receive said pins, and means for supporting the last against the ends of the pins in said holes to determine the relation, as to angularity, between the bottom face of the forepart of the shoe and the plane of the wipers in the overwiping operation.

34. A last having in the bottom of its forepart a plurality of holes located respectively near the end of the toe and near the 50 opposite sides of the last to receive last-positioning members for positioning the last relatively to means for operating on the shoe materials.

35. A last having in its bottom portion at

one end thereof three holes located at points 55 that are out of alinement with one another for use in positioning the last relatively to means for operating on the shoe materials.

36. A last having in the bottom of its forepart a plurality of holes extending inwardly to relative depths determined by reference to a plane defined by three points on the bottom of the last at the end and at the opposite sides of the toe respectively for use in positioning the last relatively to means 60 for operating on the shoe materials.

37. A last having in the bottom of its forepart three holes located at points that are out of alinement with one another and with 70 their inner ends in a plane substantially parallel to a plane determined by three points on the bottom of the last at the end and at the opposite sides of the toe respectively.

38. A last having in the bottom of its forepart a plurality of metal bushings with holes extending part way only therethrough for use in positioning the last relatively to means for operating on the shoe materials.

39. A last having in the bottom of its forepart a plurality of metal bushings located respectively near the end of the toe and near the opposite sides of the last and provided with holes extending part way only 80 therethrough, said holes extending into the last to relative depths determined by reference to a plane defined by three points on the bottom of the last at the end and at the opposite sides of the toe respectively.

40. An insole having in the bottom of its forepart a plurality of gage holes extending through it and located respectively near the end of the toe and near its opposite sides.

41. An insole having in one end portion at least three gage holes extending through it 95 and located at points that are out of alinement with one another.

42. A welt shoe insole having in the bottom of its forepart a plurality of gage holes extending through it and located respectively near the end of the toe and near its opposite sides, said holes being located 100 farther inwardly from the edge of the insole than the welt-attaching lip or rib.

In testimony whereof I have signed my 105 name to this specification.

ARTHUR F. PYM.
